(57) **CLAIM**

The ornamental design for a container for gas generator, as shown and described.

DESCRIPTION

FIG. 1 is a front perspective view of a container for gas generator, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The figures include surface shading, which represents contour and not surface ornamentation.

The broken lines in the figures illustrate portions of the container for gas generator that form no part of the claimed design. The dot-dash broken lines represent the bounds of the claimed design.
